(57) **CLAIM**

The ornamental design for a camera mounting plate with deployable attachment point, as shown and described.

DESCRIPTION

FIG. 1 is a top plan view of the new design of a camera mounting plate with deployable attachment point;

FIG. 2 is a front side view thereof, the rear side view being a mirror image thereof;

FIG. 3 is a right side view thereof;

FIG. 4 is a left side view thereof;

FIG. 5 is a bottom view thereof;

FIG. 6 is a top plan view with the attachment point deployed thereof;

FIG. 7 is a front side view with the attachment point deployed thereof, the rear side view being a mirror image thereof;

FIG. 8 is a right side view with the attachment point deployed thereof;

FIG. 9 is a left side view with the attachment point deployed thereof; and,

FIG. 10 is a bottom view with the attachment point deployed thereof.

The broken lines in all views depict environment only and form no part of the claimed design.
